RETRACTABLE KEEPER FOR DOOR
FASTENERSStacy B. Haseltine, La Grange, Ill., assignor to
W. H. Miner, Inc., Chicago, Ill., a corporation
of Delaware

Application June 18, 1947, Serial No. 755,417

5 Claims. (Cl. 292—241)

1

This invention relates to improvements in keepers for fasteners of the rotary bar type for hinged doors, and more particularly keepers which are retractable to protect the same against damage.

One object of the invention is to provide a door fastener for hinged doors of automobile trucks, comprising a rotary operating bar mounted on the truck door having keeper engaging crank members engageable with keepers mounted on the truck body above and below the door opening, wherein the lower keeper is in the form of a swinging member adapted to drop to out of the way position when the door is opened to protect the keeper against damage when the truck is backed against a loading platform or building, and wherein means is provided for automatically raising the keeper to horizontal operative position when the door is swung partly shut.

A more specific object of the invention is to provide a door fastener mechanism, as set forth in the preceding paragraph, wherein the lower keeper is pivotally supported on the truck body to swing to retracted pendant, out of the way position, and the door which carries the fastener mechanism is provided with a projecting arm which engages the keeper when the door is swung toward partly closed position to swing the keeper to operative position to be engaged by the corresponding crank member of the rotary operating bar to actuate the door.

Other objects of the invention will more clearly appear from the description and claims herein-after following.

In the accompanying drawings forming a part of this specification, Figure 1 is a rear elevational view of a portion of the body of an automobile truck, provided with a door opening and a pair of hinged doors, illustrating my improvements in connection therewith. Figure 2 is a vertical sectional view, on an enlarged scale, corresponding substantially to the line 2—2 of Figure 1. Figure 3 is a horizontal sectional view, corresponding substantially to the line 3—3 of Figure 2, showing the door partly open and the lower keeper held in horizontal position by the projecting cam arm of the door. Figure 4 is a view similar to Figure 2, illustrating the position of the parts when the door has been swung open beyond the position shown in Figure 3. Figure 5 is a top plan view of the lower keeper shown in Figures 1 and 2. Figure 6 is a horizontal sectional view of the back plate of the bottom bearing bracket of my improved mechanism and the cam arm of said plate, said view being on the same plane as Figure 3. Figure 7 is an end ele-

2

vational view of Figure 6, looking from left to right. Figure 8 is a view similar to Figure 2, illustrating another embodiment of the invention. Figure 9 is a top plan view of the back plate of the bearing bracket shown in Figure 8, and the cam arm carried thereon. Figure 10 is an elevational view of the supporting bearing plate for the swinging keeper shown in Figure 8. Figure 11 is a plan view of the keeper shown in Figure 8. 10. In said drawings, 10 indicates the rear wall of an automobile truck having a door opening 11 therein, closed by a pair of hinged doors 12 and 13. Each door is provided with the usual hinges 14 along the vertical outer side edges thereof, 15 by which the door is swingingly supported. As is common practice, the door 12, which is that first closed, and the door 13 have their meeting edges beveled and so inclined that the door 13 will maintain the door 12 in closed position and wedge the same shut when the door fastener is actuated to force the door 13 closed. The door 13 carries the usual rotary operating bar 15, which is disposed vertically and has keeper engaging crank members 16—16 at the top and bottom ends thereof, provided with crank pins 17—17 adapted to cooperate with slotted keepers of well-known design for forcing the door 13 open or camming the same shut, the upper crank member having camming engagement with the upper keeper, which is indicated by 117, the latter being fixed to the truck body above the door 13. The bar is supported for rotation on the door 13 by upper, lower, and intermediate bearing brackets, the upper and intermediate bearing brackets, 30 which are indicated by 18 and 19, being of any well-known design. The bar 15 is arranged to be rotated by an actuating lever 20, which is pivotally connected to the bar to be dropped to pendant position when the door has been forced open, and adapted to be locked in position by a latch 21 of any well-known character when the door has been forced to tightly closed position by the fastener mechanism.

In carrying out my invention as illustrated in the embodiment shown in Figures 1 to 7 inclusive, I provide broadly a swinging lower keeper A with which the lower crank member of the operating bar cooperates, a bearing or guide bracket B for the lower end of the operating bar, and a cam arm C on the bracket B, which is engageable with the keeper A to swing the same to operative horizontal position and lock it in that position.

The keeper A is pivotally supported between its ends on the end sill of the truck, which end

sill is indicated by 22, the end sill being of channel-shaped cross section and provided with an opening 23 within which the keeper is mounted. As shown most clearly in Figures 3 and 4, the opening 23 extends through the vertical web of the end sill and also through the forward portion of the lower flange of the sill, thus providing sufficient clearance to permit the keeper to drop to pendant vertical position. A bolt 24, extending through an enlarged portion 26 of the keeper and through the flanges 25-25 of a U-shaped bracket or plate 27, located at the opening 23 of the sill and welded to the inner side of the vertical web and to the top and bottom flanges of the end sill 22 at the opening 23, supports the keeper for swinging movement.

The keeper A has a short arm and a long arm extending in opposite directions from the pivotal axis of the same, the short arm being in the form of a tail portion 28 extending rearwardly from the pivot of the keeper, as viewed in Figure 2. The long arm, which is indicated by 29, projects forwardly beneath the door and is provided with a transverse, upwardly opening, inclined cam slot 30 at its outer end within which the crank pin 17 of the lower crank member 16 is engageable to cam the door 13 open or closed in the usual manner. As shown in Figures 2 and 4, the main body portion or web of the plate 27 is cut out or recessed, as indicated at 31, to provide clearance for the tail or short arm 28 of the keeper when the latter is swung to horizontal position.

The bearing or guide bracket B for the lower end of the operating bar 15 is of two-part construction, comprising front and back plates 32 and 33 between which the shank 34 of the lower crank member of the bar 15 is journaled, the plates 32 and 33 being fixed to the lower end of the door 13 by securing bolts 35 extending through the plates and the body of the door. The back plate 33 of the guide bracket B has the cam arm C formed integral therewith, the arm C being in the form of a right angular bent portion, extending in horizontal direction beneath the door 13 and projecting a considerable distance rearwardly of the same.

The main body portion of the arm C is downwardly offset with respect to the lower edge of the door 13, as clearly shown in Figure 4, and presents a flat underneath surface. The arm C is preferably reenforced on its upper side by lengthwise extending ribs 36-36 along opposite side edges thereof. The inner end portion of the arm C, that is, where it merges with the back plate 33 of the bracket B, is laterally widened to provide ears 37-37 by which it is secured to the underneath edge of the door, being fixed by screws 38-38 extending through said ears and into the door. This arm C is so located that it is in substantial alignment with the tail 28 of the keeper A when the door is moved toward closed position and is adapted to engage the tail 28 to swing the keeper upwardly from the pendant position shown in Figure 4 to the horizontal position shown in Figure 2, when the door is being manually swung to partly closed position, preliminary to camming the door closed by rotation of the bar 15. As shown in Figure 2, the top surface 39 of the tail or short arm 28 of the keeper is preferably offset with respect to the main body portion of the keeper to assure true flat faced contact between the arm C and the tail portion 28 to lock the keeper in horizontal position during the time that camming action takes place between the lower crank member and the lower keeper.

The operation of the improved door fastener shown in Figures 1 to 7 inclusive is as follows: Assuming that the doors 12 and 13 are in the closed position shown in Figures 1 and 2 and that the doors are to be opened, the attendant, after unlatching the lever 20, swings the same toward the right from the position shown in Figure 1, thereby rotating the bar and the keeper engaging crank members 16 thereof to cam the door outwardly in the usual manner. When the door 13 has thus been forced partly open, the crank pins 17 of the crank members 16 are disposed at the entrance opening ends of the cam slots of the keepers in position to clear the outer walls of said slots so that both doors may be readily swung open by the attendant without interference, the crank pin of the lower crank member being in the position shown in Figure 3. As the door 13 is swung outwardly by the attendant from the position shown in Figure 3 toward fully open position, the arm C is withdrawn from engagement with the tail or short arm 28 of the keeper A, permitting the latter to swing to the pendant position shown in Figure 4.

In forcing the door 13 closed, the reverse procedure is followed. The doors 12 and 13 are first swung to partly closed position by the attendant. As the door 13 is being swung toward the partly closed position shown in Figure 3, the arm C engages the tail or short arm of the keeper A, swinging the keeper upwardly from the pendant position shown in Figure 4 to horizontal position, and locking the same in the latter position, as shown in Figure 3. The door 13 is then forced tightly closed by rotation of the bar 15, the top and bottom crank members cooperating with the top and bottom keepers A and A to cam the door shut in the usual manner. During this action, the arm C effectively blocks the keeper A against swinging movement as shown in Figure 2. The keeper A thus functions in the same manner as the usual fixed lower keeper of the rotary door fastener during the operation of forcing the door tightly closed and camming the same partly open.

As will be evident, when the keeper A is in its retracted pendant position, as shown in Figure 4, it is disposed inwardly clear of the inner end of the truck and thus protected against damage when the truck is backed against any object, such as a loading platform.

Referring next to the embodiment of the invention shown in Figures 8 to 11, inclusive, the construction is the same as that of the embodiment illustrated in Figures 1 to 7, inclusive, with the exception that the retractable keeper is supported on the outer side of the end sill of the truck and swingable against said end sill when dropped to pendant position.

In carrying out the invention as illustrated in Figures 8 to 11, inclusive, I provide a swinging lower keeper D, a bearing bracket E for the lower end of the operating bar, and a cam arm F on the bracket E, cooperating with the keeper D.

The keeper D is pivotally supported between its ends on the end sill 40 of the truck, having trunnions 41-41 journaled in bearing seats 42-42 provided in a supporting plate 43 riveted to the outer side of the end sill 40. The keeper D has a short arm 44 and a long arm 45, which extend in opposite directions from the pivotal axis thereof. As shown in Figure 8, when the keeper D is in horizontal raised position, the long arm 45 extends outwardly or forwardly beneath the operating bar 15 and the short arm 44 extends inwardly of the sill and is accommodated in the open-

ing 46 of the plate 43 and a registering opening in the vertical web of the sill 40. The long arm is provided with a cam slot 47 at its outer end within which the crank pin 17 of the lower crank member 16 of the operating bar has camming engagement. The short arm 44 is in the form of an enlarged head portion with which the arm F is engageable to swing the keeper to horizontal position and lock the same in that position.

The bearing bracket E is similar to the bracket B hereinbefore described, comprising front and back plates, the back plate carrying the rearwardly extending arm F which operates to swing the keeper D from pendant to horizontal position when the door 13 is swung toward closed position by the attendant.

I claim:

1. In a door fastener for a hinged door of a container, the combination with a rotary operating bar mounted on the door; of a pivoted keeper mounted on the container; a cam arm on said door engageable with the keeper to swing the same to operative position; and crank means on said bar engageable with the keeper.

2. In a door fastener for a hinged door of a container, the combination with a rotary operating bar mounted on the door; of a keeper swingingly supported on the container for movement from pendant to horizontal position; an inwardly projecting cam arm on the door engageable with the keeper to swing the same to horizontal position as the door is swung toward closed position; and crank means on said bar engageable with said keeper for forcing the door tightly closed.

3. In a door fastener for a hinged door of a container, the combination with a rotary operating bar mounted on the door; of a keeper pivoted between its ends on said container for swing-

ing movement from pendant to horizontal position, said keeper having a short arm and a long arm extending oppositely from the pivotal axis thereof; a cam projection on said door engageable with the short arm of the keeper to swing said keeper from pendant to horizontal position when the door is being swung partly closed; and cam means on said bar engageable with the long arm of said keeper for forcing the door partly open or tightly closed.

4. In a door fastener for a hinged door of a container, the combination with a vertically disposed, rotary operating bar mounted on the door, said bar having a keeper engaging crank member at the lower end thereof; of a bearing bracket on the door supporting said bar for rotation; a swinging keeper pivotally supported between its ends on said container for swinging movement from pendant to horizontal position, said keeper having a long arm and a short arm, said long arm having a cam slot at its outer end within which the keeper engaging crank member is engageable to force the door open or closed; and an arm on said bracket extending beneath the door and projecting rearwardly therefrom, said arm being engageable with the short arm of the keeper when the door is being moved to closed position to swing said keeper from pendant to horizontal position.

5. In a door fastener for a hinged door of a container, the combination with an operating bar on said door having keeper engaging means thereon; of a keeper mounted on the container for movement from retracted, inoperative position to extended operative position; and an arm on said door engageable with said keeper for moving the same from retracted to extended operative position by closing movement of the door.

STACY B. HASELTINE.
